AUXILIARY PRESSER

Woldemar Heinitz, Chemnitz, Germany, assignor
to Schubert & Salzer Maschinenfabrik Aktien-
gesellschaft, Chemnitz, Germany

Application August 19, 1935, Serial No. 36,938
In Germany August 27, 1934

2 Claims. (Cl. 66—98)

The present invention relates to an auxiliary presser for flat knitting machines which are adapted for the manufacture of stockings in a single operation and in which, during the manufacture of the heel parts, the loops of the instep portion or the loops of the intermediate part of the stocking are placed in suspense. 5

Auxiliary pressers acting upon a portion of the frame needles are known already. These auxiliary pressers act upon the frame needles themselves or upon the head of these needles in such a manner, that the needle is bent away from the presser edge. Moreover, auxiliary pressers are also known by means of which frame needles to 15 be pressed only are bent against the presser edge, whereas the frame needles not to be pressed are not affected at all.

All devices of this kind have the disadvantage, that by this particular action the frame needles 20 are unduly stressed, whereby bendings and other damages are caused.

Furthermore, subdivided pressers are also known which are so constructed that only those parts of the presser remain in connection with 25 the frame needles, which are used to press the needles. These latter devices are very complicated in construction and require rather exactly machined devices for effecting their movements and obtaining proper bearing, as, naturally, subdividing of the presser results in a similar insecurity or uncertainty of bearing as the subdivision of the needle bar in the general construction of the loop forming elements.

Now, all these disadvantages are obviated according to the present invention by the fact, that 35 neither the needle bar nor the presser has any subdivisions, but particular pressers are provided in the range of the heel portions only which pressers are brought into active position during the manufacture of the heel parts only. To prevent special modifications of the devices, effecting 40 the movements of the other loop forming elements, precautions are taken, that the auxiliary pressers lie between the frame needles and the presser during the pressing operation proper only, so that the remaining general loop formation 45 may be performed in the normal position of the frame needles. The position of the frame needles, therefore, adapts itself to the altered pressing point during the pressing of the rows of loops of the heel portions and during the shifting of the new loop of the thread upon the beard of the needle immediately following the pressing operation only.

55 In the accompanying drawing one embodiment

of a device according to the invention is shown by way of example. In this drawing:

Fig. 1 shows a side elevation of an auxiliary presser according to the invention in the position of rest, i. e. during the manufacture of ordinary 5 rows of loops,

Fig. 2 illustrates in side elevation the position of the auxiliary presser during the manufacture of rows of loops of the heel portions in which 10 the loops of the instep portion and the intermediate part of the stocking respectively are placed in suspense and

Fig. 3 is a detail front elevation of the support carrying the presser instruments.

The jack sinker bearing 1 forming part of a 15 conventional flat knitting machine has the usual presser edge 2 with which the frame needles 3 may cooperate.

Fixed on a rock shaft 4, journaled in the frame of the machine, not shown in the drawing, are 20 levers 5, one or more for each division, carrying a presser supporting means in each division of the knitting machine. This presser support may for instance, as shown in Fig. 3, consist of a substantially T-shaped member 6 to which a presser bar 25 7, carrying presser instruments 8, is fixed. This supporting member may, however, also consist of a plate, a frame or the like. The presser supports are so arranged as to be individually movable and each of the presser supports is subjected to the 30 action of a spring 9 one end of which is fixed to the presser supports, while the other end is connected to the hub 5a of the corresponding lever 5. The spring 9 tends to pull the presser supports towards the jack sinker bearing 1. Provided at each of 35 the arms 6 of the presser supports is a cam 10 having an inclined surface 10a. Counter-cams 11 having an inclined surface 11a are provided at the jack sinker bearing 1.

Fixed on the shaft 4 is a cam lever 12 carrying 40 at its free end a shiftable roller 13 which may be laterally adjusted by means of a fork 15 mounted upon a shiftable rod 14. Fixed upon a cam shaft 16 rotatably mounted in the frame of the machine is a circular disc 17 and a cam 18. By shifting the rod 14, the roller 13 may be brought into engagement with the circular disc 17 or the cam 18, depending on the position the rod 14 occupies at the end of the shifting movement.

During the manufacture of ordinary rows of 50 loops, the roller 13 runs upon the circular disc 17 and the presser instruments 8 occupy the position shown in Fig. 1 in which their heads are situated beneath the presser edge 2 of the jack sinker bearing 1. In this position of the instru- 55

ments 8 the inclined surfaces 10a of the cams 10 bear against the inclined surfaces 11a of the counter-cams 11.

As in any normal legging frame, the frame needles 3 are pressed directly at the presser edge 2.

If now the knitting of the heel portions is started, the rod 14 and with it the fork 15 is shifted, so that the roller 13 is brought into the path of the cam 18. Under the action of the cam 10 18 the cam lever 12 is raised, whereby the rock shaft 4 is rocked. By means of the levers 5, fixed upon the rock shaft 4, the presser supports are lifted. During the lifting movement, the presser supports are, by means of the inclined surface 15 10a of the cams 10 rising on the inclined surface 11a of the counter-cams 11, shifted to the right in the drawing. The presser instruments 8 are hereby moved in the same direction, being brought, during the lifting movement, in front of the presser edge 2 and are pressed against the latter under the action of the springs 9. (Fig. 2).

Pressing of the frame needles 3, lying in the range of the presser instruments, is continued, whereas, by any conventional means known in the art, the frame needles adapted to work the middle portion of the fabric are now prevented from reaching the face at which pressing is effected.

The presser edge 2 is, therefore, advanced or

shifted forwardly about the distance a (Fig. 2), corresponding to the thickness of the presser instruments 8. Of course, on account of this advance of the presser point, simultaneously the position of the frame needles must, in a well known manner, also correspondingly be altered during the manufacture of the rows of loops of the heel portions. Furthermore, during the sinking operation, the sinker jacks must also be held in a correspondingly altered position.

What I claim is:

1. In an auxiliary presser for flat knitting machines adapted for the manufacture of stockings in a single operation, in combination a jack sinker bearing, a rock shaft, levers fixed upon said rock shaft, supports carrying presser instruments pivotally connected to said levers, a cam operated lever, cooperating cam means provided at said bearing and at said supports and a spring urging each of said supports towards said jack sinker bearing.

2. In an auxiliary presser as set forth in claim 1, in which each of said cooperating cam means is provided with an inclined surface so arranged, that each of said presser supports is, during upward movement, shifted laterally with respect to said jack sinker bearing.

WOLDEMAR HEINITZ.
